ATTORNEY.

UNITED STATES PATENT OFFICE.

OSCAR E. CLOUD, OF WICHITA, KANSAS.

VENTILATOR.

1,346,633.

Specification of Letters Patent.

Patented July 13, 1920.

Application filed September 29, 1919. Serial No. 327,345.

To all whom it may concern:

Be it known that I, OSCAR E. CLOUD, a citizen of the United States of America, and resident of Wichita, in the county of Sedgwick and State of Kansas, have invented certain new and useful Improvements in Ventilators, of which the following is a specification, reference being had to the accompanying sheet of drawings.

10 This invention relates to ventilators for the tops of air stacks, and belongs to the type known as "siphon" ventilators.

The invention and improvement consists in the provision of a number of vertical-radial deflectors applied to the inner and outer faces of the hood, and to the novel combinations and arrangements therewith of a conical deflector and other allied parts whereby an improved siphonage is produced 20 and a free outflow of gases and air through the ventilator maintained.

Referring now to the accompanying drawings:

Figure 1 is a side elevation of a ventilator 25 constructed according to the invention; Fig. 2 is a central vertical section of same; Fig. 3 is a top plan view of same; Fig. 4 is a detail view of material for one vertical-radial deflector; Fig. 5 shows a modified form of the 30 hood in elevation.

The ventilator comprises for its principal parts, the body tube 1, (which forms an extension of the upper end of an air stack) the annular wind-guard 2, the cap 3, the 35 conical deflector 4, and the frusto-conical hood 5.

The hood 5 is supported from the tube 1, and the wind-guard 2 is supported from the hood 5. The cap and deflector 3—4 are supported in the ring 2 by means of brackets 6.

The hood 5 is held in concentric position by a series of pairs of sheet-metal fins 7 and 8 which are vertically and radially disposed. The inner fins, 7, have right-angled flanges 45 7' by which they are secured to the body tube 1 by rivets 9, and have similar flanges by which they are secured to the hood 5. The outer fins 8 are formed with flanges 8' fastened to the hood with rivets 10. The 50 outer fin of each pair is in the same plane as the companion inner fin 7. These fins constitute air-deflectors, which have the function of directing horizontal winds upwardly and through the wind-guard 2. By 55 reference to the drawings, it will be noted that the conical cap 3 is sufficiently large at

its base to more than cover the eduction pipe 1 thereby preventing rain from entering said pipe; the conical deflector 4 integrally depending from the cap 3 has a base but 60 slightly smaller than the base of said cap, the apex of said deflector 4 hangs below the plane of the rim of the hood 5, said rim being flared as clearly seen in Fig. 2.

The wind-guard is secured to the upper 65 ends of the outer fins 8 by small bolts 12 instead of being riveted, so that the parts carried by the wind-guard may readily be removed for cleaning or other purposes.

The upper ends of each pair of fins 7—8 70 are cut obliquely, so as to meet the upper rim of the body tube 1.

The lower edge 13 of each segment of the hood 5 is cut upon an arched curve, as shown, instead of straight across as they 75 might be (see Fig. 5). This cutting-away is a feature of improvement for this reason:—it causes and permits a greater volume of moving air to enter the space between the hood and the body tube: this air will 80 mainly be drawn upward, as indicated by darts on the drawing, and thus the total siphoning force acting upon the air within the stack will be augmented. It will be especially noted that the oblique cut given 85 the upper portions of the fins 7 and 8 allow for a free circulation of air above the top orifice of the eduction pipe 1 and that the conical deflector 4 dropping down below the flared rim of the hood 5, that is within the 90 orifice of said hood, the said deflector cooperates with said flared rim and oblique upper portions of the fins to turn the gases and the assisting air currents as indicated by the arrows without the eddying and objectionable features now a condition that 95 obtains in common practice.

In laying out a pair of the fins 7—8, a single piece is cut to the shape shown by Fig. 4, then the piece is divided along the 100 central diagonal line.

In small sizes of ventilator, four vertical-radial deflectors will be employed; in large sizes, a larger number. Such modifications may be employed as lie within the scope of 105 the appended claim.

Having described my invention, what I claim and desire to secure by Letters Patent is:

A ventilator comprising a tubular eduction pipe, upwardly tapering fins integral therewith and vertically radiating around

the outside thereof; a frusto-conical hood surrounding said pipe and extending above the upper end thereof and having an upper outwardly flared rim portion, said hood being supported by outer inclined edge portions of said fins; downwardly tapering fins without said hood, radiating in the same vertical plane with said first mentioned fins; an annular wind guard horizontally supported from upper portions of said outer fins, the lower edge of said guard lying in a plane below the plane of the flared rim of said hood; a conical cap, supported from and within said windguard, covering said

eduction pipe; a conical deflector, having its 15 base within said cap and its apex depending therefrom downwardly to a point below the plane of the flared rim of said hood and within said hood orifice; the upper edges of said inner and outer fins extending obliquely from the upper edge of said eduction pipe to the base of said windguard; all substantially in the manner disclosed and for the purposes as specified.

OSCAR E. CLOUD.
